No. 37,042.

Patented July 12, 1904.

UNITED STATES PATENT OFFICE.

EDWIN J. BUSH, OF NEW YORK, N. Y.

DESIGN FOR A DOLL-HOLDER.

SPECIFICATION forming part of Design No. 37,042, dated July 12, 1904.

Application filed December 2, 1902. Serial No. 133,647. Term of patent 7 years.

To all whom it may concern:

Be it known that I, EDWIN J. BUSH, of New York, in the county of New York and State of New York, have invented a new, original, and ornamental Design for Doll-Holders, of which the following is a specification, reference being had to the accompanying drawing, forming part thereof.

The figure is a plan view of a doll-holder, showing my new device.

What I claim as new, and desire to secure by Letters Patent, is—

The ornamental design for a doll-holder as shown.

EDWIN J. BUSH.
